UNITED STATES PATENT OFFICE.

JAMES M. COOK, OF WESTMONT BOROUGH, PENNSYLVANIA.

MINE-CAR.

1,012,817.

Specification of Letters Patent.

Patented Dec. 26, 1911.

Application filed October 17, 1910. Serial No. 587,363.

To all whom it may concern:

Be it known that I, JAMES M. COOK, a citizen of the United States, residing in the borough of Westmont, in the county of Cambria and State of Pennsylvania, have invented certain new and useful Improvements in Mine-Cars; and I do hereby declare the following to be a full, clear, and exact description of the invention, such as will enable others skilled in the art to which it appertains to make and use the same.

My invention relates to buffers for railway vehicles, and more especially to mine cars, and its principal object is to provide a combined buffer-block and draw-head suitable for such cars, which consists in the provision of a device of economical and rigid construction for receiving the buffing shocks and pulling strains.

As illustrated in the drawings, the center-sill of the car consists of a timber or other member extending beyond the ends of the car. I provide these extending ends of the center-sill of the car with metallic buffers, preferably of cast steel, to prevent their being battered. The buffer-block has a clevis member integral therewith, which forms a socket for the reception of the coupling links, and has a hole for the coupling pin, so that it also serves as the draw-head.

In order to relieve the frame of the car from practically all tensile stresses, I use a continuous draft-rod which extends between the two coupling pins, having eyes in the ends thereof registering with those of the coupling block, as will be hereinafter more fully described and particularly pointed out in the appended claims.

Referring to the sheet of drawings forming part of the specification, in which like characters of reference indicate like parts throughout the views:—Figure 1 is a side elevation of a mine car embodying my invention. Fig. 2 is a top plan view of my improved buffer-block, also showing the center-sill and draft-rod in position. Figs. 3 and 4 are respectively a side elevation and an end elevation of the same. Fig. 5 is a transverse section taken on the line V—V of Fig. 2 and Fig. 6 is a longitudinal section taken on the line VI—VI of Fig. 2.

Referring to the drawings, the numeral 1 designates the center sill of the car, which, in the drawings, is illustrated as a single timber extending beyond the ends of the car, although this is not absolutely necessary, as

the center sills might be made of more than one piece of timber, or they might be of metal. Buffer-blocks 2 preferably of cast steel, are mounted on the extended ends of the sill 1 and are constructed with a head member 3 having upper and lower rearwardly extending integral flanges 4 and 5 which embrace the upper and lower sides of the ends of the center-sill. A draft-rod 6 rests upon the upper side of the center-sill and is continuous throughout the length of the car, relieving the center-sill of the major portion of the tensile stresses to which the car is subjected. The ends of the draft-rod 7 pass under an offset 7 in the upper flange member 4 of the buffer-blocks and are secured thereto by means of bolts 8 which pass through the member 4, the draft-rod 6, the center-sill 1 and a tie-rod 9, which extends 75 under the center-sill and acts as a cross-sill to tie the car structure together. The center-sill and draft-rod are preferably secured together at intervals, so that the rod also reinforces the sill when the latter receives 80 compressive forces. A clevis member 10 integral with the upper part of the buffer-block forms a socket 11 for the reception of the coupling links 12 which connects successive cars in a train. This clevis member 85 also has a hole 13 for the reception of a coupling pin 14 which registers with the eyes 15 in the ends of the draft-rods 6, and holes 16 and 17 in the center-sill and the bottom frame 5 of the buffer-blocks 2. The 90 buffer-blocks 2 are further secured to the center-sill, by means of bolts 18 which pass through holes on either side of the top flange 4, the center sill 1, and the bottom flange 5, as will be clearly seen by referring to the 95 drawings.

Although I have shown and described my invention in considerable detail, I do not wish to be limited to the exact and specific details set forth, but may use such substitutions, modifications, or equivalents thereof, as are embraced within the scope of my invention, or as pointed out in the claims.

What I claim as my invention and desire to secure by Letters Patent, is:

1. In a car, a center-sill extending beyond the ends of the car, a buffer-block mounted on either end of said sill, a clevis member formed integral with the buffer-block and extending above the same and a draft-rod 110 extending between the buffer-blocks and adapted to act as a draw bar.

2. A combined buffer-block and draw-head, comprising a head member adapted to receive impact of colliding vehicles, rearwardly extending flanges, a clevis member integral with one of the flanges, and a draft-rod secured to the center-sill and the said flange of the buffer-block.
3. In a car, a center-sill, a buffer-block mounted on each end of said sill, a clevis member integral with each buffer-block, a draft-rod extending between said buffer-blocks and having its ends secured within the buffer-blocks, holes through the buffer-blocks, sill and draft-rod, for the reception of coupling pins.
4. In a car, a center-sill, a buffer-block mounted on the end of said sill, a clevis member on the buffer-block, said clevis member forming a socket for a coupling link and a coupling pin extending through the clevis member and a portion of the buffer-block.
5. In a car, a center-sill, buffer-blocks

mounted on the ends of the said sill, a clevis member on each buffer-block, said clevis member forming a socket for a coupling-link, a draft-rod connecting the buffer-blocks and a coupling pin extending through the clevis member, the draft-rod, and the lower flange of the buffer-block.

6. In a mine car, the combination of a draw bar attached to the top of the car bottom and having a hole for a coupling pin near its projecting end, a bumper comprising a top plate divided to receive the draw bar centrally, and a buffer portion formed as an integral part of said bumper, and fitted with a hole for the coupling pin in correspondence to the hole in the end of the draw bar.

In testimony whereof I hereto affix my signature in the presence of two witnesses.

JAMES M. COOK.
